ATTORNEY

UNITED STATES PATENT OFFICE.

JEAN B. A. LA JEUNESSE, OF ALAMEDA, CALIFORNIA.

EATING APPLIANCE.

1,409,731.

Specification of Letters Patent. Patented Mar. 14, 1922.

Application filed August 21, 1919. Serial No. 318,961.

To all whom it may concern:

Be it known that I, JEAN B. A. LA JEUNESSE, of Alameda, California, have invented certain new and useful Improvements 5 in Eating Appliances, whereof the following is a specification.

This invention relates to devices for assisting cripples and others who are more or less incapacitated, in feeding themselves.

10 In carrying out the invention I mount a swinging arm, adapted to swing vertically, so that it may be operated by a foot. To this arm I attach a fork, or other utensil, which may be depressed and brought into 15 contact with morsels of food in a plate, for example, to hold the same or to seize and elevate it, in a manner similar to that when the utensil is used by hand.

In the accompanying one sheet of drawing 20 I have illustrated a form of my invention which I consider the best.

Figure 1 is a perspective view of the entire apparatus, shown in use.

Figure 2 is the upper end of the swinging 25 arm.

Figure 3 is a fork which may be used with the apparatus.

Figure 4 is a view of a standard to which the swinging arm may be pivoted.

30 Figure 5 is a view of a strap to hold the foot of the standard to a base.

In the figures: A base block 1 is held to a table 2 by a clamp 3. To the base 1 is secured the strap 4, which holds the standard 5 by the insertion of the right angled portion of the latter 6 under the strap. An arm 7 is pivoted to the top of the standard 5 by the pivot 8. At the end of the arm 7 is pivoted the fork 9, by means of the 40 thumb screw 10, entering a slot 11 in the base of the fork. A shoulder 12, on the end of arm 7, engaging the edge of the fork, limits the play of the latter. The fork is depressed by a cord 13, attached to arm 7 at a suitable point 14, and extending over pulleys 15 and 16, to a treadle 17. A third pulley 18, opposite pulley 16, adapts the device for left hand or right hand use, according to the disability of the user. The fork, 45

being depressed by the cord 13, may engage the morsel of food 19 on the plate 20, as seen in dotted lines in Figure 1. The food may then be held, whilst being served, and the served portion then raised, as seen 50 in full lines in Figure 1, for further action. The arm 7, with the fork and morsel of food

are raised to the upright position, seen in full lines in Figure 1, by a weight 21. The weight 21 is slidable upon the arm, for purposes of adjustment, and is secured by a set 60 screw 22. I prefer the weight to a spring because it is more uniform in its action, and I prefer it to an auxiliary treadle, because it is automatic.

Having thus described my invention, and 65 an embodiment of it, in the full, clear and exact terms required by law, and knowing that it comprises novel, useful and valuable improvements in the art to which it pertains, I here state that I do not wish to be 70 limited to the precise construction and arrangement of the several parts, as herein set forth, as the same may be variously modified by a skilled mechanic without departing from the spirit of the invention. 75

What I claim and desire to secure by Letters Patent of the United States, is the following, to-wit:—

Claims:

1. An instrument of the class described, 80 having a swinging arm, means for depressing said arm into engagement with a portion of food and adjustable weight on said arm for elevating the same.

2. An instrument of the class described, 85 having a swinging arm, means for depressing said arm to engage a portion of food, and a weight upon said arm for elevating the same.

3. An instrument of the class described, 90 comprising a base, a removable standard mounted upon said base, a swinging arm pivotally mounted upon said standard, a utensil pivotally secured at one end of said arm, a cord for depressing said arm and a weight upon said arm for elevating the same. 95

4. An instrument of the class described, 100 comprising a base adapted to be clamped upon a table, a standard secured to said base, a swinging arm pivoted to said standard, a utensil at one end of said arm, a weight upon said arm adapted to elevate said utensil, and means for depressing said utensil into engaging position consisting of a treadle provided with means engaging said swinging arm. 105

In testimony, that I claim the foregoing I have hereto set my hand this 16th day of Aug., 1919, in the presence of two witnesses.

JEAN B. A. LA JEUNESSE.

Witnesses:

W. S. BATES,
FLORENCE L. WOLFE.
